Frank Freeman

UNITED STATES PATENT OFFICE.

CHARLES M. WILLS, OF ATLANTIC CITY, NEW JERSEY, ASSIGNEE TO THE AMERICAN TRANSOM CO., INC., OF PHILADELPHIA, PENNSYLVANIA, A CORPORATION OF DELAWARE.

VENTILATOR.

Application filed March 1, 1928. Serial No. 258,220.

My invention relates to ventilators and refers particularly to ventilators through which vision is always impossible and through which the passage and non-passage 5 of air and light are controllable.

While the passage or non-passage of air through ventilators is of prime importance, it is also equally desirable that sight therethrough should be impossible.

10 My invention presents a simple and effective means for accomplishing these advantageous results and is adaptable for doors or transoms.

The device of my invention comprises 15 among other elements a closure means whereby air, light and dust may be effectively prevented from passing therethrough by means of abutment between the closure means and the wings of the device, thus completely closing 20 the openings through which these elements pass when the device is in open position.

Further, it is of such construction that vision through it is always effectively prevented.

25 In the accompanying drawings illustrating one form of the device of my invention, similar parts are designated by similar numerals.

Figure 1 illustrates one form of my device installed in the upper portion of a door.

30 Figure 2 is a vertical cross-section of one form of my device.

Figure 3 is a section through the line 3—3 of Figure 2 showing the device in closed position.

35 Figure 4 is a section similar to Figure 3 showing the device in open position.

The particular form of the device of my invention comprises a casing composed of a top channel member 10, a bottom channel 40 member 11 and the end channel members 12 and 13. The sides of the device consist of the plates 14 and 15 having longitudinally spaced inwardly inclined wings 16, 16, the extremities of the wings of one side being 45 spaced from the extremities of the wings of the other side.

Between the wings of the two sides and extending between the ends of the device and between its top and bottom is a movable 50 closure member 17 having a plurality of vertical openings 18, 18, therein.

The openings 18, 18 of the closure member 55 17 are positioned in alignment with the side plates 14 and 15 and staggered with respect to the openings between the wings 16, 16,

in such a manner that when the closure member 17 is brought into abutment with the wings 16, 16 of either side, the openings between the wings will be closed preventing sight and the passage of air through the device as shown in Figure 3, and that when the closure member 17 is spaced from the wings air will pass through the device but vision will be prevented therethrough as shown in Figure 4.

60 The illustrated means for moving the closure member 17 into open and closed position consists of oppositely positioned rods 19, 19, having the fixedly attached operating members 20, 20 exterior of the device, the interior 70 extremity of each rod 19, 19, being attached to the closure member 17.

Each rod 19 carries a revolute pinion 21 meshed with a rack 22 carried by an end member of the device. Each rod 19 also carries 75 a stop collar 23, limiting its outward movement.

Two guide rods 24, 24, pass through openings in the upper portion of the closure member 17 and are affixed to upper portions of 80 the sides 14 and 15.

85 The operation of the device is as follows:—

When the device is in the position shown in Figure 4, air can pass therethrough although sight is not possible through the device.

85 When it is desired to close the device from the passage of air and light, the rods 19, 19, are moved inwardly, thus bringing the closure member 17 into abutment with the wings 16, 16 of the side 14.

90 My device, therefore, presents an inexpensive and effective ventilator through which sight is always impossible and through which the passage or non-passage of air and light may be easily controlled.

95 I do not limit myself to the particular size, shape, number or arrangement of parts as shown and described, as these are given simply as a means for clearly describing the device of my invention.

100 What I claim is:—

1. In a visionless ventilator, in combination, a casing; two parallel sides to the casing having a plurality of openings therein; a plurality of inwardly extended wings carried by the marginal edges of said openings; a vertically positioned horizontally movable closure between the two sides having a plurality of openings therein, said openings being staggered with respect to the side open- 110

- ings and means exterior of the casing for moving said closure into abutment with the wings of one side, whereby the openings in said side will be closed.
5. 2. In a visionless ventilator, in combination, a casing; two parallel sides to the casing having a plurality of openings therein; a plurality of inwardly extended wings carried by the marginal edges of said openings; 10 a vertically positioned horizontally movable closure between the two sides having a plurality of openings therein, said openings being staggered with respect to the side openings, guiding means for said closure between 15 said sides and means exterior of the casing for moving said closure into abutment with the wings of one side, whereby the openings in said side will be closed.
3. In a visionless ventilator, in combina-

tion, a casing; two parallel sides to the casing having a plurality of openings therein; a plurality of inwardly extended wings carried by the marginal edges of said openings; a vertically positioned horizontally movable closure between the two sides having a plurality of openings therein, said openings being so positioned that air will pass through the device when said closure is not in abutment with the wings of one side and will be prevented from passage therethrough when said closure is in abutment with the wings of said side, guiding means for said closure between said sides and means exterior of the casing for moving said closure.

Signed at New York city in the county of 35
New York and State of New York this 7th
day of February, 1928.

CHARLES M. WILLS.
